(No Model.)

S. M. HERBER.
PILLOW BLOCK.

No. 403,471.

Patented May 14, 1889.

UNITED STATES PATENT OFFICE.

SAMUEL M. HERBER, OF LINCOLN, ILLINOIS, ASSIGNOR TO THEODORE R. PEIFER, OF SAME PLACE.

PILLOW-BLOCK.

SPECIFICATION forming part of Letters Patent No. 403,471, dated May 14, 1889.

Application filed September 24, 1888. Serial No. 286,262. (No model.)

To all whom it may concern:

Be it known that I, SAMUEL M. HERBER, a citizen of the United States, residing at Lincoln, in the county of Logan and State of Illinois, have invented a new and useful Pillow-Block and Main Box or Bearing on an Engine, of which the following is a specification.

My invention relates to an improvement in pillow-blocks and journal-boxes, and more especially to that peculiar class of journal-boxes in which keys act, in conjunction with the pillow-block and box-sections, for the purpose of adjusting and holding said sections in position.

The object of the invention is to provide a journal-box provided with improved means for easily and accurately adjusting the box-sections to fit the shaft, and to form a continuous bearing for the shaft which will not brush or scrape the oil off the same.

The objects are accomplished by and my invention consists in certain novel features of construction and combinations of parts more fully described hereinafter, and particularly pointed out in the claims.

Referring to the accompanying drawings, Figure 1 is a side elevation of my pillow-block, showing the manner of securing the journal-boxes thereto. Fig. 2 illustrates a top plan view of the boxes, showing the intersecting joints. Fig. 3 is a side elevation of the cap-adjusting wedges, tightening-plate, and means for securing the same. Fig. 4 is a broken sectional detail view of one of the journal-boxes, clearly showing the depressions and projections. Fig. 5 is an end view of the pillow-block, showing the upwardly-projecting link or loop. Fig. 6 is a perspective view of the pillow-block complete; and Fig. 7 is a vertical transverse section taken on the line $x-x$ of Fig. 2.

In the drawings, the reference-letter a indicates a pillow-block provided with the usual vertical jaws, $b b'$, located a distance apart to form a seat for the journal-box, which is divided vertically and composed of two similar halves or box-sections, $c c'$, fitted snugly in the seat of the pillow-block, to allow a limited movement toward each other, and the outer ends of said box-sections are provided with

the flanges d , which fit upon the outer sides and jaws of the pillow-block, and thereby hold the boxes in their seat and prevent longitudinal play of the same.

The opposite meeting edges of the boxes at 55 the top and bottom of the bearing are provided with a series of overlapping intermeshing projections, n , and corresponding recesses, o , the projections on the edges of each box being located opposite and entering corresponding recesses in the opposite edges of the other box, as clearly shown, and the inner faces of the inner series of projections are curved to correspond to the curve of the bearing. The object of this overlapping and joining the meeting edges of the boxes is to form a continuous bearing for the shaft and avoid the abrupt continuous edges and the space between the same, which would result if the adjoining edges of the boxes were straight and 65 plane instead of formed into intermeshing overlapping projections in sections.

A cap, e , fits over the seat in the pillow-block and over the upper edges of the jaws b and b' , and is provided with end flanges to fit 75 upon the outer faces of said jaws, and said cap carries the wedge-shaped keys $f f'$, which are located between the inner faces of the pillow-block jaws and the outer sides of the boxes, so that as the keys are pushed down 80 the boxes will be forced in toward each other and the bearing contracted to more snugly fit the shaft in the same. The cap or top plate at one end is adjustably secured to the jaw b' by a set-screw, g , and at the other end is adjustably secured to the jaw b by a loop, h , secured to or formed with said jaw and projecting upwardly from the same through the cap-plate, and said plate is confined upon the same by the wedge or key i , inserted in the 85 upper end of the loop and bearing on the top of the cap. The key is prevented from slipping by a set-screw, j , extending through an arm of the loop and engaging the key.

The boxes are held to their seat in the pillow-block and are prevented from vertical or lateral play by a plate, k , bearing upon the top of the same between the flanges, and said plate is held in place by two or more set-screws, l , extending through the cap. To con- 90

tract the bearing to fit the shaft more tightly, loosen the set-screws *l* and tighten the set-screw *g*, and then drive in the wedge *i*, which operation will force down the cap-plate, and with it the keys, thereby forcing the boxes together to fit the shaft. The set-screw *j* is then tightened to hold the wedge in position, and also the set-screws *l*, to hold the plate *k* firmly upon the boxes.

10 The key *f'*, carried by the end of the cap-plate, is preferably secured to said cap by a set-screw, *g'*, to hold the same in the proper position.

15 It is evident that when the boxes are first placed in position the projections at the adjoining edges of the same do not extend very far into their respective recesses; but as the bearing is worn away and the boxes are adjusted so as to snugly fit the shaft the projections extend farther and farther into the recesses, and thus overlap the bottoms of the recesses more and more.

What I claim is—

1. The combination of a pillow-block having the vertical jaws forming a seat between them, the vertically-divided box located in said seat and consisting of a pair of similar box-sections adjustable toward each other, a vertically-adjustable cap-plate, wedge-shaped 25 keys carried by the same and located between said jaws and the boxes, a plate to hold the boxes to their seat, set-screws extending through the cap-plate, a set-screw for adjustably securing one end of the cap to one of 30 said jaws, a loop extending from the opposite jaw through the cap, and a wedge upon the cap extending through the loop, for the purpose described.

2. The combination of the pillow-block having vertical jaws forming a seat between them, the vertically-divided box located in said seat and consisting of a pair of similar box-sections adjustable toward each other and having flanges fitting upon the exterior of the jaws of the block and having their adjoining edges provided with recesses and intermeshing overlapping projections, whereby a continuous bearing is formed and the boxes can be adjusted to snugly fit the shaft, and a cap-plate secured to said jaws in vertical 45 adjustment and provided with wedge-shaped keys fitting between the jaws and boxes to adjust the same, substantially as described.

3. A journal box or bearing comprising two sections surrounding and forming the bearing for and adjustable toward each other to snugly fit the shaft, and having their adjoining edges provided with corresponding series of recesses and intermeshing projections, whereby a continuous bearing is formed 50 around the shaft and over the joints between the box-sections, substantially as described.

4. A journal-box comprising two similar sections forming the bearing for the shaft and joined together to form a continuous bearing by having their adjoining edges provided with series of recesses and corresponding 55 snugly-fitting intermeshing and overlapping projections, substantially as described.

SAMUEL M. HERBER.
